BRAKING MECHANISM FOR RAILWAY CAR TRUCKS

Harry A. Moeller, Columbus, Ohio, assignor to
The Buckeye Steel Castings Company, Co-
lumbus, Ohio

Application February 15, 1939, Serial No. 256,571

3 Claims. (Cl. 188—205)

This invention relates to improvements in braking mechanism for railway car trucks, and while such improvements have been designed for an eight-wheel truck, they are equally applicable to any truck having a center bolster.

One of the objects of the invention is to provide a truck of the center bolster type in which the braking mechanism is divided into two units operated respectively by pressure fluid cylinders carried by opposite end portions of the center bolster.

Another object is to supply braking mechanism having parts constructed and arranged to reduce the overall length of the truck.

A further object is to supply braking mechanism in which the lever system is dead ended at the medial portion of the truck. By dead ending the system at the medial portion of the truck, and operating it by means of an air cylinder at each end of the truck, it is possible to reduce the amount of accumulative slack at each cylinder to one-half of that which would occur if two cylinders were used on the same end of the truck, each operating the brake shoes on one entire side of the truck.

Another object is to furnish in mechanism of this character, a novel equalizer lever guide and support.

An additional object is to supply improvements in the live end pull rod supports of the system to provide proper clearance for levers forming part of the system.

Another object is to improve the brake head structures, and to so support them that the shoes which they carry will conform to the peripheries of the wheels of the truck.

With the foregoing objects outlined and with other objects in view which will appear as the description proceeds, the invention consists in the novel features hereinafter described in detail, illustrated in the accompanying drawings, and more particularly pointed out in the appended claims.

In the drawings:

Fig. 1 is a top plan view of a truck provided with my improved braking mechanism.

Fig. 2 is an enlarged vertical sectional view of one-half of the truck, and showing certain portions of my improvements, the section being taken on the line 2—2 of Fig. 1.

Fig. 3 is a similar view, taken on the line 3—3 of Fig. 1.

Fig. 4 is an end view of the truck.

Fig. 5 is a vertical transverse sectional view, taken on the line 5—5 of Fig. 1.

Fig. 6 is a side elevation of one of the equalizer lever guides and supports.

Fig. 7 is a side elevation of the brake head of one of the end wheel brakes, and the supporting means for the same.

Fig. 8 is a sectional view, taken on the line 8—8 of Fig. 7.

Fig. 9 is a side elevation of a brake head of one of the intermediate brake shoes, and the means for supporting the same.

Fig. 10 is a vertical sectional view, taken on the line 10—10 of Fig. 9.

Fig. 11 is a fragmentary elevation of a modification.

Fig. 12 is a top plan view of an extensible and contractable supporting rod for taking up slack in the braking system.

Fig. 13 is a side elevation of the rod.

Fig. 14 is a vertical sectional view on the line 14—14 of Fig. 13.

Fig. 15 is a top plan view of the equalizer lever guide and support shown in Fig. 6.

Referring to the drawings, 11 designates end wheels, and 12 the intermediate wheels of the truck. Such wheels support axles 13 journaled in boxes 14 attached respectively to the intermediate members 15 and end members 16 of the side frames of the truck.

In the truck illustrated, equalizers 17 are pivotally supported at 18 by the intermediate members, and have their ends pivotally connected at 19 to the inner ends of the members 16. The latter support transverse bolsters 20 which in turn support the center bolster 21 having side rails 22 which extend in opposite directions in the form of arms 23. The arms of each pair terminate in a plate 24, and an air or other pressure fluid cylinder 25 is secured to such plate, preferably beneath the plate.

Each cylinder may be arranged either horizontally or inclined to the horizontal, as illustrated. By inclining the cylinder it is possible to raise the inner end of the same sufficiently to allow it to be moved back over an end axle 13, thereby reducing the overall length of the truck. Each cylinder is provided with a piston (not shown), and such pistons are connected to piston rods 26 which project in opposite directions away from the center bolster. The outer end of each rod is pivotally connected at 27 to the medial portion of an equalizer lever 28 which has its end portions offset relatively to its medial portion, with such end portions arranged closer to the center bolster than said medial portion.

The ends of each equalizer lever are pivotally

connected at 29 to the outer ends of links 30 (Figs. 3 and 4), and the inner end of each link is pivotally connected at 31 to the lower end of a lever 32, the upper end of the latter being pivotally supported at 33 by an extension 34 of the center bolster. A link 35 pivotally connects the medial portion of the lever 32 to the upper end of a lever 36, the medial portion of the latter being pivotally supported at 37 by a combined link and guide member 38, the latter having an offset extension 39 that is slidable in a guide sleeve 40 united with one of the end members 16 of the side frame system and provided with a lower wearing plate 41 on which the arm 39 slides. The member 38 has a telescopic joint at 42, provided with holes 43 and 44 which may be brought into alignment and receive a connecting pin 45. In this way, wear in the parts of the braking system may be taken up at each side of each end of the truck.

The member 38 extends over one of the end axles 13, and its inner end is pivotally connected to the medial portion of a lever 46, the upper end of the lever being pivotally suspended from a slidible rod 47 carried by a guide 48 which in turn is supported by an end member 16 of the side frame system. The opposite end of the rod pivotally supports a lever 49 having its medial portion pivotally connected by a link 50 to the medial portion of a similar lever 51 which is pivotally supported at its upper end by a brake hanger bracket 52 integral with a medial member 15 of the side frame system.

The lower end of each lever 36 is connected by a link 53 to a brake beam 54, the latter having its ends connected to the lower ends of levers 55, the upper ends of which are pivotally connected at 56 to the end members 16 of the side frame system.

The lower end of each of the levers 46, 49 and 51 are pivotally connected at 57 to links 58 which in turn are pivotally connected to the intermediate brake beams 59 and 60. The beams 59 are supported by links 61 carried by a hanger bracket 62 forming part of spring seats 62 (Fig. 5), which support the springs 63 (Fig. 3) that carry the transverse bolsters.

The brake beams 60 are supported by links 64 which have their upper ends pivotally connected to brake hanger brackets 65 forming part of the intermediate members of the side frame system.

The levers or links 55 carry brake heads 66 which support brake shoes 67 for the end wheels. The brake heads and the means employed in connecting them to the links 55 are best shown in Figs. 7 and 8. In these figures it will be noted that the link is provided with a bushing 67a that supports a cylindrical pin 68. The latter has an enlarged cylindrical head 69 journaled in a bushing 70 in an ear 71 forming part of the brake head. The pin also passes through a bushing 72 formed in the opposite ear 73 of said head.

The outer end portion of the pin is threaded for the reception of a nut 74 which bears against a washer 75 employed in compressing a coil spring 76 between it and an end of the bushing 72. By tightening the nut it is obvious that the turning movement of the brake head 66 about the pin may be controlled so that the brake head may be set to properly apply the brake shoe to an end wheel of the truck, but yet permit such shoe to conform to the periphery of the wheel.

The pin has an angular extension 77 which may be engaged by a wrench to prevent the pin

from turning while the nut 74 is being manipulated.

Each link 55 has an aperture 78 at its lower end for the attachment of the brake beam 54. Each of the suspension links 61 and 64 for the intermediate brake heads 79 (Figs. 9 and 10), is provided at its lower end with a bushing 80 for the reception of a bushing 81 that surrounds a cylindrical extension 82 of one of the intermediate brake beams 59 or 60. The latter has an enlarged cylindrical portion 83 arranged in a bushing 84 positioned in one of the ears 85 of the brake head 79. The opposite ear 86 of the brake head is provided with a bushing 87 that also surrounds the bushing 81. Each end of the brake beam is threaded to receive a nut 88 which bears against a washer 89 acting to compress a coil spring 90, which construction permits the control of the turning movement of the brake head about the cylindrical extension 82.

From the above it is apparent that my construction is such as to permit use of the same brake heads on hanger levers at outside end positions, and on brake beams at intermediate positions.

Before describing the operation of the mechanism, I direct attention to the equalizer lever guide which is best illustrated in Figs. 6 and 2. Each of these members preferably consists of a piece of angle iron 91 arranged at an incline in the event that the air cylinder 25 is inclined. The angle iron has a vertical wing 92 and a lateral wing 93, the latter being provided with a wear plate 94 for slidable support of the equalizer lever 28. The lateral wing also has apertures 95 for the reception of bolts 96 that are employed in securing the guide to one of the plates 24 of the center bolster.

A post 97, preferably of strap metal, is secured to the vertical wing 92 by any suitable means such as welding 98, and it supports an upper guide member comprising a substantially angular part consisting of a lower part 99, an upstanding part 100, and a top horizontal part 101. The part 99 is parallel to, and arranged above, the wing 93, and its edge is welded at 102 to an edge of the post 97. A weld 103 connects a side edge of the part 101 to an edge of the post, and another weld 104 secures the part 101 to the top of the post. The member made up of the parts 99, 100 and 101 is reinforced by a strut 105 which has its lower end portion parallel with the part 99 and secured thereto by welding 106. The upper end portion of the strut is parallel with the part 101 and is secured to that part and the upper end portion of the post respectively, by welds 107 and 108. Apertures 109 are provided in the part 100 for the reception of bolts 110 employed in securing the guide and support to the extension of the center bolster.

In operation, when air or any other suitable fluid is introduced into the cylinders 25 under pressure, the pistons in the cylinders will force the piston rods outwardly, and they in turn will move the equalizer levers 28 in opposite directions away from one another.

Referring now to Fig. 3, it will be noted that the motion of the lever will cause the following to occur at each side of one-half of the truck. Link 30 will pull the lower end of lever 32 forwardly, causing link 35 to swing link 36 in a clock-wise direction about its pivotal support 37, which in turn will cause link 53 to swing link 55 in a counter-clock-wise direction and apply

an end brake shoe 67 to one of the wheels 11. Simultaneously, the link element 38 will be pulled to the right, causing lever 46 to swing in a clockwise direction and pull the link 47 toward the right. This will result in swinging lever 49 in a clockwise direction and pulling rod 50 to cause link 51 to swing in a counter-clock-wise direction about the axis arranged at its upper end. Obviously, this will result in the application of the brake shoes which are associated with the intermediate beams 59 and 60.

Of course, the brakes on the other end of the truck are operated by the cylinder at that end of the truck, in the same manner. The dead ending of the lever system at 52 reduces the amount of slack which accumulates in the lever system, due to the wearing of the parts. Adjustment for slack in the system may be made at the telescopic joints 42. Slack in the system increases the amount of piston travel required to apply the brakes. This slack is of two kinds. The slack due to pin and bushing wear which is accumulative, so that a long system may accumulate a large amount of slack, requiring excessive piston travel with only nominal wear at each pin connection. The slack in the system due to brake shoe and wheel wear is not accumulative, and the length of the system does not affect the amount of piston travel required to take up this type of slack. If the shoe wear is one-half inch, and the leverage ratio between the piston and the brake heads is 1 to 9, the piston travel required to take up the one-half inch at the shoes is $9 \times \frac{1}{2}$ equals $4\frac{1}{2}$ inches, and this is true for one shoe or any number of shoes.

By dead ending the system at the central portion of the truck and operating it by means of an air cylinder at each end of the truck, it is possible to reduce the amount of accumulative slack at each cylinder to one-half of that which would occur if two cylinders were used on the same end of the truck, each operating the brakes on one entire side of the truck.

Each equalizer lever 28 is offset, as before stated, to provide clearance, when the piston is fully extended, between the ends of the lever and certain valves and parts (not shown), suspended from the body of the vehicle. The clearance between the ends of the lever and these body parts is also increased by this offset construction in the case where new shoes might be applied to one side of the truck only, while worn ones were used on the other side. In such a case, the new shoes would come in contact with the wheels first, and the equalizer lever would then turn about the pin 27, and the end of the lever 28 on the side having the greatest amount of slack would be extended farther from the truck. The offset construction of the equalizer lever serves to increase clearances between the body parts and the end of the lever under such conditions.

In order to support and guide the lever system near the end wheel, the rod 38 is provided with the offset portion 39, and this effects the requisite clearance for the operation of lever 32.

Referring to the equalizer lever guide and support shown in Fig. 6, it will be noted that the outer end of the support being open, it is possible for the equalizer lever 28 to move outward from the truck slightly beyond the ends of the support. By employing this open end type of construction, it is possible to make the support considerably shorter than with a closed end construction. In this manner, the overall length of the truck is also materially reduced.

Reverting to the trunnion type brake heads shown in Figs. 7 to 10 inclusive, it will be noted that the design is such as to be used either at the outside of the end wheels or at the intermediate positions, and the brake head may turn about its support in order to properly align each brake shoe with the braking face of the wheel. In order to prevent the vibrations and jolts due to travel and gravitational pull on the head itself from moving the brake head out of its proper alignment, its position relative to the hanger lever is fixed by means of friction which is maintained by the spring. The compression of the spring is so adjusted that the friction is insufficient to prevent the brake head from moving, when the brakes are applied, to compensate for wheel and shoe wear. The enlarged cylindrical surfaces 69 and 83 are provided to stabilize the brake heads.

Instead of dead ending the levers 51 by brake hanger brackets 52, I may, as shown in Fig. 11, connect these levers to a floating rod 120 that is supported by the intermediate member 15a of the side frame system.

From the foregoing it is believed the construction, operation and advantages of the invention may be readily understood by those skilled in the art, and I am aware that changes may be made in the details disclosed, without departing from the spirit of the invention, as expressed in the claims.

What I claim and desire to secure by Letters Patent is:

1. In a railway car truck of the type having wheel-supported axles, journal boxes mounted on the axles, side frame systems carried by the journal boxes, springs supported by the side frame systems, and bolster means supported by said springs and including a center bolster, the improvement which comprises a first supporting lever pivotally suspended from an end portion of said center bolster, a second lever, a link connecting the upper portion of the second lever to a medial portion of the first lever, a bracket supported by one of the side frame systems, a substantially horizontal supporting rod pivotally connected to the medial portion of the second lever and having an offset portion extending past said first lever and slidably guided by said bracket, braking shoes operatively connected to the rod and second lever, and means for actuating the first lever whereby the brake shoes are applied to a wheel of the truck.

2. In a railway car truck of the type having wheel-supported axles, journal boxes mounted on the axles, side frame systems carried by the journal boxes, springs supported by the side frame systems, and bolster means supported by said springs and including a center bolster, the improvement which comprises a first supporting lever pivotally suspended from an end portion of said center bolster, a second lever, a link connecting the upper portion of the second lever to a medial portion of the first lever, a bracket supported by one of the side frame systems, a substantially horizontal supporting rod pivotally connected to the medial portion of the second lever and having an offset portion extending past said first lever and slidably guided by said bracket, braking shoes operatively connected to the rod and second lever, and means for actuating the first lever whereby the brake shoes are applied to a wheel of the truck, said rod being extensible and contractable for taking up slack in the braking system.

3. In a railway car truck of the type having a center bolster, a pressure fluid cylinder carried by an end portion of the bolster, a piston rod associated with the cylinder, an equalizing lever having its medial portion pivotally connected to the piston rod, and guide and supporting members for said lever arranged at opposite sides of the piston rod and secured to said end portion of the center bolster, the improvement in each of said guide and supporting members which com-

5
10
prises an angle iron portion having a vertical wing and a lateral wing, the lever being adapted to slide on said lateral wing, a post secured to the vertical wing, an angular member secured to the post and having a portion arranged parallel to and spaced from said lateral wing, and a strut rigidly secured to and connecting the end portions of the angular member.

HARRY A. MOELLER.
